Primary Examiner — Jae Liang*Assistant Examiner* — Ji Sun Yoon(74) *Attorney, Agent, or Firm* — Schwartz Law Firm, P.C.(57) **CLAIM**

The ornamental design for a cooler as shown and described.

DESCRIPTION

FIG. 1 is a top perspective view of a cooler, showing our new design;

FIG. 2 is another top perspective view of the cooler;

FIG. 3 is a bottom perspective view of the cooler;

FIG. 4 is a front view of the cooler;

FIG. 5 is a bottom view of the cooler;

FIG. 6 is a rear view of the cooler;

FIG. 7 is a top view of the cooler;

FIG. 8 is a right side view of the cooler; and,

FIG. 9 is a left side view of the cooler.

The broken lines in the figures depict portions of the cooler that form no part of the claimed design.
